UNITED STATES PATENT OFFICE.

WILLIAM WALPOLE, OF OXENDEN, ONTARIO, CANADA.

SLEIGH.

961,469.

Specification of Letters Patent. Patented June 14, 1910.

Application filed September 13, 1909. Serial No. 517,532.

To all whom it may concern:

Be it known that I, WILLIAM WALPOLE, of the village of Oxenden, in the county of Grey and Province of Ontario, Canada, have 5 invented certain new and useful Improvements in Sleighs; and I hereby declare that the following is a full, clear, and exact description of the same.

This invention relates to a double bench 10 knee for connecting the upper part of the sleigh to the sleigh runner, so that the upper part of the sleigh will be maintained in its normal position regardless of the irregularities of the road over which the sleigh is 15 traveling, by permitting either runner of the sleigh to oscillate for a reasonable distance independently of the other.

For an understanding of the invention reference is to be had to the following description and to the accompanying drawings 20 in which:—

Figure 1, is a perspective view of part of the sleigh showing the construction of the sleigh knee. Fig. 2, is a vertical cross section of the sleigh knee and runner. Fig. 3, 25 is a side view of the sleigh knee.

Like characters of reference refer to like parts throughout the specification and drawings.

30 Fitted on the top of the sleigh runner *a* is a grooved base *b* having flanges *k'* and *m'* which overlap the runner sides *d* and *e*, and projecting from the base *b* is a block *f* having two semi-circular rockers *g* and *h* arranged in parallel planes and separated by an unoccupied annular space *i*.

Between the semi-circular rockers *g* and *h*, with its circumferential edge *k* in contact with the bottom of the annular space *i* is a 40 rocker *l* for the bench bed *m*. The under side of the bench bed *m*, on either side of the rocker *l* is concaved to receive the curved surfaces of the semi-circular rockers *g* and *h*, and is provided with flanges *n* and *o* to engage 45 the outer side faces of the rockers *g* and *h* so as to prevent the lateral move-

ment of the parts, this movement being further prevented by the engagement of the rocker *l*, with the inner faces of the rockers *g* and *h*. The rockers *g*, *h*, and *l* are rockably connected by a pin *p*, which passes through annular apertures *q* and *r* in the rockers *g* and *h*, and through an annular aperture *s*, in the rocker *l*.

At the ends of the arms *v* and *w* of the 55 bench bed *m* are bench plates *x* and *y* having grooves *t* and *u* in which are contained the ends of the beams *a'* and *b'* the arms *v* and *w* being braced by webs *z* and *z'* integral with the bench bed *m*. A sand board 60 *c'* is rigidly attached to the beams *a'* and *b'*, near their centers to support the bunk *d'* and the end of the reach *e'* which are fastened to the said sand board *c'* near its center by means of the king bolt *f'* which passes 65 down through the bunk *d'*, reach *e'* and sand board *c'*. The ends of the arms *v* are formed with slotted hinge parts *v'*, to which, and to the toes of the runners, are connected 70 rods *v''*.

Having thus fully described my invention what I claim as new and desire to secure by Letters Patent is:

In a sleigh in combination, a runner, a 75 sleigh knee consisting of a base attached lengthwise to the runner and having side flanges engaging the outer surfaces of the side faces of the runner, and two upwardly extending rockers, a bench bed having a downwardly extending rocker to enter the 80 unoccupied space between the rockers of the base, and bench plates attached crosswise of the bench arm, the cross beams being supported on the arms of the bench plate, a hinge member at the front end of the bench 85 arms, and a stay rod pivotally connected to the hinge member and to the runner.

Toronto, September 13th, 1909.
WM. WALPOLE.

Signed in the presence of—

C. H. RICHES,
H. L. GRIMBLE.
